3 Claims. (Cl. 200—11)

In order to make desired connections in electrical or electronic circuits or to modify their operation, it is usual to employ a number of members such as for example switches of all kinds, multi-pin plugs and sockets, relays, and so on, and these are constituted, wholly or in part, by assembling contact members on a rigid insulating support, said contact members being fixed on or in the insulating support through which they completely pass.

Hitherto the fixing of such conductive members on the support was effected in practice either by directly moulding them in the material of the support or by mechanical means such as screws and nuts or eyelets, or by crimping or riveting and so on. All these means inevitably cause stresses in the materials and these stresses may cause the destruction of the insulating support, particularly if the latter is made from porcelain or a brittle resin for example, or its deformation where it is of a laminated construction for example. It may even happen that owing to variations of temperature and/or humidity, these stresses become changed, thus often causing a deformation of the insulating support and hence impairing the conditions of operation.

It is an object of the invention to remedy these disadvantages.

Considered from a most general point of view, the invention provides, in the case of such assemblies that each contact member and two elements constituting the insulating rigid support shall have a staggered relationship in such a manner that said contact members are completely fixed in position when the two elements have been joined together along two plane faces. The assembly will then have been achieved without causing any stress in the materials which are brought together, and the above mentioned drawbacks are substantially avoided. Besides this advantage, the cost of the assembly is substantially reduced, since the manufacturing operations become extremely simple and do not entail any complicated tooling.

Accordingly, the invention consists in an electrical circuit connection member of the kind comprising one or more contact members fixed in relation to a rigid insulating support through which they extend, in which the rigid insulating support is constituted by two elements, having plane faces which are rigidly joined together along a plane into which recesses formed in the thickness of the said elements open from each side of the support, each recess of one of the elements co-operating with a recess of the other element, each two co-operating recesses both partly extending in the prolongation of the other and also partly masking the adjacent element, the part of each contact member which passes through the insulating support being formed and dimensioned so as to completely fill up two co-operating recesses.

In order that the invention may be more clearly understood, reference will now be made to the accompanying drawings which show two specific embodiments thereof by way of example only, and in which:

FIGURE 1 shows an assembly comprising certain parts of a rotary selector switch, in plan view from the side or face including the contact surfaces of the studs,

2

FIGURE 2 is a cross-section along the line II—II of FIGURE 1.

FIGURE 3 shows a perspective view of one of the contact studs of FIGURES 1 and 2 inserted in the insulating support which latter is shown in section,

FIGURE 4 shows the stud of FIGURE 3, in section along its fixing plane,

FIGURE 5 shows an assembly of a second embodiment of rotary selector switch employing flat contact studs also in plan view from the side or face including the contact surfaces of the studs.

FIGURE 6 is a cross-section along the line VI—VI of FIGURE 5.

FIGURE 7 shows a perspective view of one of the contact studs of FIGURES 5 and 6 inserted in the insulating support which latter is shown in section, and

FIGURE 8 shows the stud of FIGURE 7, shown in section along its fixing plane.

Referring to the drawings, the first specific embodiment to which FIGURES 1, 2, 3 and 4 relate, concerns the fixed part of a rotary selector switch comprising cylindrical contact members cut from a rod of a suitable metal, and being fixed in position by the rigid insulating support through or into which they extend.

The rigid insulating support is constituted by two elements 1 and 2 which are rigidly joined together along two plane faces and assembled by three eyelets 3 or by any other suitable assembly means.

In the thickness of each of these elements 1 and 2 there is provided a series of cylindrical recesses intended to receive a series of contact members or studs 4, 4', disposed in such a manner that when said elements 1 and 2 are assembled together, each recess of one element co-operates with a recess of the other, the two co-operating recesses being each partly in the prolongation of the other and being each partly masked by its adjacent element.

Moreover, in that part of the contact member 4, 4' which passes through the two elements 1 and 2, constituting the insulating support, the section is offset in the fixing plane by pushing or twisting one part in relation to the other, (FIG. 4) which thus divides the member into two relatively eccentric parts.

When effecting the assembly, all these parts 4 or 4' of the contact members which are situated on the same side of the insulating support are introduced respectively into the recesses of the corresponding element 1 or 2, and then all the other parts of the members are introduced into the recesses of the other element in such a manner that, when the two elements are joined together, each pair of co-operating recesses is completely filled up by the part of the contact member which passes through it.

In this state, each contact member is prevented on all sides from displacement and is perfectly fixed in relation to the insulating support without causing any stress in the materials.

The second embodiment to which FIGURES 5, 6, 7 and 8 relate, also concerns the fixed part of a rotary selector switch, but in this case comprising flat contact members cut from a strip of suitable metal and these parts are, as in FIGURES 1 to 4, fixed by the elements of the rigid insulating support through which they pass.

The rigid insulating support is constituted by two elements 11 and 12 joined together along two plane faces and assembled by three eyelets 13 or by any other suitable means.

In the thickness of each of these elements 11 and 12 is provided a series of slot-shaped recesses to receive a series of contact members 14, 14' disposed in such a manner that, when said elements 11 and 12 are assembled together, each slot of one element co-operates with a

slot of the other, the two co-operating slots crossing each other in their geometrical centre in such a manner that the ends of each are masked by the adjacent element 11 or 12, similar to the arrangement of FIGURES 1 to 4.

In this embodiment also, in that part of the contact member 14, 14' which passes through the two elements 11 and 12, the thickness of the section is cut into from each extremity, preferably for the same length, in order to partially separate the member into two parts whose planes are then caused to cross each other by imparting a twist to the remaining common section.

When assembling, all the parts 14 or 14' of the contact members which are situated on the same side of the insulating support are respectively introduced into the slots of the corresponding element 11 or 12, and all the other parts of members are introduced into the slots of the other element in such a manner that, when the two elements 11 and 12 are joined together, each pair of co-operating slots is completely filled up by the part of the contact member which passes through it.

In this state each contact member is prevented on all sides from displacement and is perfectly fixed in relation to the insulating support without causing any stress in the materials.

I claim:

1. An electrical circuit contact assembly comprising a rigid insulating support constituted by two flat plate-like apertured elements, said elements being secured together face to face with the apertures in the respective elements

paired but having a partial displacement from precise superposition, and each said aperture containing a contact member, said contact member fitting into and filling said aperture, whereby the one contact member of each pair is prevented from intruding into the space of its pair contact member by said partial displacement, and the assembly is thus kept substantially free of mechanical strain upon said supports.

2. A member as claimed in claim 1, in which the contact members comprise cylindrical studs having two parts which are eccentrically disposed relative to each other, each of said apertures being of cylindrical shape.

3. A member as claimed in claim 1, in which the contact members have a flat shape and comprise two parts which are staggered relative to each other, each of said apertures being rectangular.
